UNITED STATES PATENT OFFICE.

JOHN EDWARD CARNEY, OF MONTGOMERY, ALABAMA.

GAME APPARATUS.

SPECIFICATION forming part of Letters Patent No. 738,771, dated September 15, 1903.

Application filed July 13, 1903. Serial No. 165,378. (No model.)

To all whom it may concern:

Be it known that I, JOHN EDWARD CARNEY, a citizen of the United States, residing at Montgomery, in the county of Montgomery and State of Alabama, have invented a new and useful Game, of which the following is a specification.

My invention relates to games; and it has for its object to produce a device of this character which will be simple of construction, inexpensive to manufacture, and one which will be at once interesting, amusing, and instructive.

To these ends the invention comprises the novel details of construction and combination of parts more fully hereinafter described.

In the accompanying drawing the figure is a view of a game chart or board embodying my invention having the game-pieces disposed thereon.

Referring to the drawing, 1 indicates my improved chart, which is of rectangular form and ruled or otherwise subdivided to produce an enlarged central square 2 and smaller end squares 3, the marginal space between the central square 2 and the edge of the chart being ruled transversely to form spaces 4 of uniform width and extending between the corner-squares 3 one space adjacent to one side of each square and constituting the entrance-space of the game, as more fully herein-after described, being designated in some suitable manner, but preferably by coloring, the colors of the various entrance-spaces contrasting.

The central square 2 is subdivided, as herein shown, to form four sector-shaped spaces 5, each having at its center a circular spot 6, bearing the vowel "U," said spaces 5 being disposed one in each corner of the square and producing therein a central space 7, the marginal lines of which are inwardly curved. The central space 7 is divided to form a small square 8, disposed centrally thereof, and a pair of spaces 9, disposed upon each side of the square between the same and the marginal line of the space, said spaces being arranged diagonally of the square 2. The spaces 5 are each marked "Goal," while the small central square 8 is marked "Court center," and they, together with the corner-squares 3 and the blanks between the spaces 9, are preferably

of contrasting colors to impart to the chart or board an attractive appearance.

10 indicates the game-pieces, preferably in the form of disks of any suitable material and each bearing upon one of its faces an alphabetical character, there being provided twenty of the pieces, each bearing one of the consonants, four pieces each bearing one of the vowels "A E I O," and four other pieces each bearing upon one face the word "and" and upon the other face the sign character "&," these latter pieces being designated in the game as "guards," while the remaining pieces 15 are designated as "vowels" and "consonants," respectively.

In practice the players, which may vary from two to four, are each provided with four game-pieces bearing, respectively, the vowels "A E I O" and with four guards bearing the word and character "and" and "&," as above described. The twenty pieces bearing the consonants are then well mixed and distributed, five in each of the corner-spaces 3, with their lettered sides up. Each player then places upon his entrance-space one of the vowels and one of the guards, the vowels being selected consecutively. Two dice are employed, which are first thrown to determine the first play, which of course is gained by the one throwing the highest number. After the play begins each player throws the dice in turn and moves his vowel and guard over the spaces 4 under certain fixed rules, according to the numbers thrown, one vowel and one guard being thus moved entirely around the marginal track of the chart and finally passing from the entrance-space at which it started into the adjacent goal 5, it being the primary object during the travel of the vowels around the board to properly enter them under certain governing rules into the corner-spaces 3, whereby the player so entering the space will capture and be entitled to remove therefrom one of the consonants and place the latter in his goal. Such capturing of the consonants from the corner-spaces can, however, only be accomplished by throwing a number which will exactly carry the vowel from its position upon the track into the corner-space.

A further object of the game is to capture the vowels or guards of an opponent, which may be effected under certain rules and con-

ditions, and when so captured the vowels or guards are placed in the goal of the capturing party and are employed, in connection with the consonants therein at the end of the 5 game, for the formation of words, whereby points in the game are scored, as more fully explained hereinafter. An additional feature of the game resides in the fact that a player may under certain rules and conditions pass 10 through his goal 5 and the central court 7 into the goal of an opponent and employ the consonants and vowels contained therein in connection with his own vowel for the formation of words and the consequent scoring of 15 points in the game. The vowels of each player are entered consecutively into the game, one vowel being moved entirely around the course and into the player's goal or captured before the entrance of a second vowel, 20 whereas the consonants may when captured from the corner-spaces be selected at the will of the player, only one consonant at a time being, however, secured. At the termination of the game—or, that is, after the 25 vowels of each player have entered the goals—each player employs all of the lettered pieces which during the progress of the game he has succeeded in accumulating in his goal for the formation or spelling of words of four or more 30 letters each, in which connection the letter "U" at the center of the goal and also the word "and" borne upon one face of the guards is employed, it being understood that words are formed with the word "and" by prefixing or 35 suffixing other letters thereto, and the number of words so spelled determines the number of points which each player obtains in the game, a word of four letters counting a certain number of points, those of five letters 40 counting a higher number of points, and so on. During the formation of the words at the end of the game each player proceeds in turn, while the remaining players give close attention, and if the player forming the word 45 misspells a word he may be challenged, and

when so challenged must discontinue the formation of the word and forfeit the number of points for that particular word to the one by whom he is corrected. Thus it will be seen that the game is not only highly interesting and amusing, but is also very instructive, and may be readily played by any one. 50

It is to be understood that while I believe the chart herein illustrated to be the best adapted for the purpose and the character 55 of the game herein set forth to be the most amusing and interesting form possible it is to be understood that minor modifications may be made in the chart and that the rules governing the game may be variously modified 60 without departing from the spirit of my invention.

Having thus described my invention, what I claim is—

1. A game comprising a chart having corner-spaces and intermediate successive spaces, a series of game-pieces initially disposed in the corner-spaces, and a plurality of game-pieces designed for travel over the intermediate spaces, the advance of said pieces 65 being controlled by numbers determined by chance, one set of said pieces bearing alphabetical consonants and the other set vowels. 70

2. A game comprising a chart having corner-spaces, and intermediate successive spaces, a series of game-pieces initially disposed in the corner-spaces and each bearing an alphabetical consonant, and a plurality of game-pieces bearing alphabetical vowels and 75 designed for travel over the intermediate 80 spaces, the advance of the vowels being controlled by numbers determined by chance.

In testimony that I claim the foregoing as my own I have hereto affixed my signature in the presence of two witnesses.

JOHN EDWARD CARNEY.
